GRINDING APPARATUS

Filed Dec. 2, 1924

INVENTOR
J. A. Samuel B. Haffenstall
by Edward A. Lawrence,
his attorney.

UNITED STATES PATENT OFFICE.

SAMUEL B. HEPPENSTALL, OF PITTSBURGH, PENNSYLVANIA, ASSIGNOR TO HEPPENSTALL FORGE AND KNIFE COMPANY, OF PITTSBURGH, PENNSYLVANIA, A CORPORATION OF PENNSYLVANIA.

GRINDING APPARATUS.

Application filed December 2, 1924. Serial No. 753,462.

My invention relates to grinding apparatus, and more particularly to grinding cylinders equipped with supporting and safety banding means.

5 The principal object of this invention is to supply an improved type of supporting or safety banding for grinding-cylinders, whether the cylinders are in one or more pieces. It is difficult, if not impossible with 10 banding of the mechanical or clamp type, to secure accurate and intimate contact between the banding and the abrasive material of which the cylinders are composed. The difficulty is particularly great with cylinders 15 composed of a circular series of segments. In cases of mechanical or clamp banding, the results are uncertain owing in part to the degree of skill exercised by the workmen who apply the bands. Furthermore much 20 time is lost in adjusting the bands.

Another object of my invention is to provide for an improved mounting of the grinding cylinder on the arbor or rotary shaft.

Referring to the accompanying drawing, 25 Fig. 1 is an end elevation of a grinding cylinder equipped with my invention; Fig. 2, a section on the line II—II of Fig. 1, parts being broken away; Fig. 3, an enlarged broken and sectional view of a fragment 30 taken from the side of the grinding cylinder showing one of the bands; Fig. 4, an enlarged broken view taken in section along the line IV—IV in Fig. 1, and Fig. 5, an enlarged broken view showing a portion of 35 one of the bands and intermediate clips.

On the drawings, 1 designates the spindle or arbor of a grinding machine supported and driven by any suitable means. The arbor has the reduced end 2 which projects 40 through the hub 3 and has its outer end 4 threaded and provided with the nut 5 which clamps the hub between the said nut and the shoulder 6 on the arbor. The hub has the peripheral flange 7 which overlies the rear 45 face of the chuck or holder ring 8, lag screws or bolts 9 being passed through the said flange and into the said ring to rigidly connect the hub and the ring together. The hub is provided with a circular concentric portion 10 which fits into the annular axial 50 opening 11 of the holder ring 8.

The face of the ring opposite the face to which the hub 3 is attached has the annular recess, channel or trough 12 whose

lateral walls are preferably provided with 55 annular grooves 13 to afford anchorage for cementitious material 14 deposited in the channel 12 between the lateral walls of the channel and the inner and outer faces of the hollow grinding cylinder 15 having its 60 rear end or base seated in the said channel 12. The material 14 may be melted sulphur, Portland cement, or the like, which is poured in a liquid or semi-liquid state into the spaces between the cylinder faces, and the 65 lateral walls of the channel 12, the material anchoring in the grooves 13 to prevent movement of the cylinder in the ring 8.

The cylinder is shown composed of an annual series of segments 16 separated at 70 their bases by the cementitious material 14^a which is continuous with the cementitious material at the inner and outer faces of the segments or cylinders but extends outwardly preferably to the outer face of the channel 75 12.

For banding or supporting from without the cylinder 15, I provide one or more bands 18, each comprising several turns of wire 17 wound in a helical manner with the successive turns of each band contiguous. Both ends of the wire in each band are held in place by a metal clip 19 enclosing the band, the ends of the clip being soldered or otherwise connected together. The ends 17 of the 80 wire in each band extend beyond the clips and these ends are bent away from the band close to the clip to prevent any possibility of the ends escaping from the clip. To hold the turns of wire, which form a band, snugly 85 together and in place, I prefer to provide additional clips 19^a which are spaced around the band. The diameter of the band is somewhat larger than the external diameter of the cylinder 15 in order to provide a space 90 between the band and the cylinder for cementitious material, as will be explained.

The bands 18 are formed by winding the wire on a suitable mandrel and securing the ends of the wire by means of the clips 19 and the continuous turns of wire together by the intermediate clips 19^a. The bands thus formed are preferably of proper diameter to fit the cylinder loosely.

The cylinder is then positioned with its axis vertical and the free ends of the segments uppermost. The spaces between contiguous segments are then closed at their

outer ends by the clay dams 20 to prevent cementitious material entering said spaces, said dams extending outwardly sufficiently to almost contact with the bands when the latter are in place.

A dam 21 composed of clay or the equivalent is then laid on the top outer wall of the channel 12 and the first band 18 is placed on this dam 21. The cementitious material 22 is then introduced into the said space between the band and the cylinder up to the level of the top of the band 18. A second annular dam 23 of clay or the like is then placed on the first band 18, and the second ring 18 is placed on this dam. The cementitious material 22 is poured into the space between the cylinder and the second band. A third dam 24 is placed on the second band 18 and the third band is placed thereon, and cementitious material 22 is again poured into the space between the cylinder and the third band. When the cementitious material 22 has hardened the clay dams 20, 21, 23, 24 are then knocked away, and the cylinder is ready for use.

Additional bands may, if required, be applied in the same manner, the free end portion of the cylinder being left without any banding so that its free end may be used for grinding. When the free end of the cylinder has been worn away to the line where the outer band 18 interferes with grinding, the latter is cut and removed. Each band is removed only as it becomes necessary to expose another length of the cylinder by reason of the wearing away of its outer end down to each band.

In the drawings I have shown a plurality of bands, but it will be understood that one or any number of bands, as may be considered preferable, may be employed.

The hub 3 may be integral with the ring 8, but it is advantageous to make the ring

separable from the hub as it enables the ready removal of the ring whose cylinder 45 has been worn to its limit and the immediate and easy substitution of a ring which has been refilled or fitted with a new abrasive cylinder.

The banding is preferably composed of 50 steel wire, preferably copper coated so as to resist the action of rust. However the banding may be either a continuous piece of metal of preferred shape of cross-section, or a series of such pieces riveted or welded in 55 a manner similar to that used in making ordinary hoops for barrels, kegs and the like.

I claim—

1. In a grinding apparatus, an arbor, a 60 holder secured thereto and rotatable coaxially therewith, a grinding cylinder secured to the holder and rotatable coaxially with the holder, metallic banding surrounding the cylinder and spaced therefrom, and cementitious material connecting the banding and the cylinder, the banding being composed of a helically-wound length of metal.

2. In a grinding apparatus of the character described, the combination with a rotatable holder having an annular recess in its face and a grinding cylinder comprising a plurality of segments arranged in annular series and having their butt-ends seated and secured in said recess, of a metal banding 70 for said segments surrounding said segments and independent of said holder, said banding being of suitable diameter to fit loosely about said segments and a filling of cementitious material between the segments and said banding whereby said banding is held in position, said banding being formed of a helically coiled wire.

Signed at Pittsburgh, Pa., this 28th day of November, 1924.

SAMUEL B. HEPPENSTALL.
